UNITED STATES PATENT OFFICE.

JAMES BURNS, OF BROOKLYN, AND ALEXANDER BUCKMAN, OF SCHODACK DEPOT, ASSIGNORS OF ONE-HALF TO JAMES R. DOWNER AND FRANK P. HARDER, BOTH OF CASTLETON, NEW YORK.

CIGARETTE-MACHINE.

SPECIFICATION forming part of Letters Patent No. 394,554, dated December 18, 1888.

Application filed March 1, 1888. Serial No. 265,801. (No model.)

To all whom it may concern:

Be it known that we, JAMES^s BURNS, of Brooklyn, in the county of Kings, and ALEXANDER BUCKMAN, of Schodack Depot, in the county of Rensselaer, and both in the State of New York, have invented a new and useful Improvement in Cigarette-Machines, of which the following is a specification.

Our invention relates more particularly to machines for forming cigarettes with tobacco wrappers, and whether the wrappers are of tobacco or paper they are cut of the proper size to form a cigarette, and the cigarettes are rolled singly and produced complete one at a time.

Our improved machine includes means whereby the proper quantity of filler to form a cigarette is placed in a pocket, and then after the wrapper has had paste applied to it the wrapper and filler are rolled in the pocket, in order to form a perfect cigarette and to lap and paste the wrapper. In our improved machine we employ, in combination with parallel endless chains or travelers, cross-bars extending between them and wheels for moving such chains or travelers, an apron or webs secured to said cross-bars and having a surplus of length or slack between the cross-bars, a pocket and a reciprocating plate or feeder on opposite sides of the apron, the feeder serving by its movement to push into the pocket the quantity of filler for the cigarette, the wrapper and a loop of the apron, and the pocket closing upon its contents as the feeder recedes, and an apron-pulling device, whereby the slack in the portion of apron which forms the loop is drawn forward and caused to roll the contents of the pocket to form a cigarette. The pocket, which is below the apron, is composed of a stationary member, which consists of a roller mounted in stationary bearings, but free to turn in them, and a movable cam-actuated member or jaw, which, when it closes upon the loop of the apron, serves to so present the forward edge of the wrapper that the first rolling movement of the cigarette will cause the wrapper to properly lap upon the forward edge of the wrapper, and thus roll a perfect cigarette.

The invention consists in novel combinations of parts, which are hereinafter particularly described, and pointed out in the claims.

In the accompanying drawings, Figure 1 is a longitudinal section of a machine embodying our invention. Fig. 2 is a plan of the machine. Fig. 3 is a transverse section of the machine upon about the plane indicated by the dotted line *x x*, Fig. 1. Fig. 4 represents gearing, whereby the apron-pulling device is driven, and whereby the endless chains or travelers are also driven, the gearing comprising a yielding connection, whereby the apron-pulling device is permitted to operate continuously, notwithstanding that the endless chains or travelers are periodically locked against movement. Fig. 5 is a sectional elevation of the parts forming the pocket and the cam for operating the movable member or jaw of that pocket, including also portions of the apron, the feeder, and the paste-applying device, said Fig. 5 showing the parts in the positions which they occupy when the feeder is just about pushing the filler into the pocket. Fig. 6 is a view corresponding to Fig. 5 of most of the parts there shown, and showing the position of the parts when the feeder has pushed into the pocket a portion of the filler, the wrapper, and enough of the apron to form a loop. Fig. 7 illustrates the several parts shown in Figs. 5 and 6 in the positions which they occupy after the feeder has receded and after the pocket has closed upon the wrapper and filler, and Fig. 8 is a similar section of the same parts in the positions which they occupy after a cigarette has been rolled and the pocket opened to permit the withdrawal of the cigarette from it. Figs. 5 to 8, inclusive, are upon a larger scale than the preceding figures, and similar letters of reference designate corresponding parts in all the figures.

A designates endless chains or travelers, which are arranged at a little distance apart, and are connected by cross-bars *A'*.

B *B'* designate parallel shafts, which are mounted in suitable boxes, *b b'*, in the side frames, *C*, of the machine. Upon the shaft *B* are mounted chain-wheels *B² B³*, and upon

the shaft B' are fast chain-wheels B^4 . The chain-wheels B^2 B^3 are loose upon the shaft B , and motion for driving the chains A is first imparted to the wheel B^2 , thence through one chain to the wheels B^4 and shaft B' , and thence through the other chain to the wheel B^3 . We have represented screws b^2 as applied to the boxes b' for adjusting them in the side frames, C , and thus regulating the tension of the chains or travelers A .

Extending between and secured to the cross-bars A' is an endless apron, D , which may be composed of a single piece, or may consist of shorter pieces or webs secured to the cross-bars, so as to form in effect an endless apron. The apron D may be of any suitable fabric—such, for example, as india-rubber cloth—which will offer a smooth surface and which will yet not stretch materially. The portions 15 of apron D which extend between the cross-bars A' are much longer than is required to extend between such cross-bars if they were stretched taut, and therefore there is offered in the apron between each two cross-bars a 20 considerable amount of surplus or slack. Upon one side of the apron—that is, below the upper travel of the apron D —is a pocket, E , which will be more fully hereinafter described, and on the opposite side—that is, 25 above the upper travel of the apron D —a reciprocating feeder, F . This feeder consists of a flat plate, which works within a channel-way, F' , and operates in conjunction with a bar or straight-edged knife, f , to cut off a 30 proper quantity of filler and push the filler downward upon the apron D exactly opposite the pocket E .

G designates a feeding-apron, which passes over rollers g and a driving drum or roller, g' , and is moved in a direction indicated by the arrows in Fig. 1. The prepared tobacco for the filler is spread out as evenly as possible upon the apron G , and is by said apron carried forward slowly and presented beyond 40 the knife f directly in the path of the feeder and cutter. We have shown the lower edge of this feeder and cutter as concave in the direction of its width, and this lower edge forms in conjunction with the plate or piece 45 f a cutter for neatly and efficiently separating the required quantity of filler, which projects beyond the cutter or plate f from the filler or layer which is upon the apron G .

The feeder F is suitably guided in the channel F' , and at its upper end it is pivoted at f' to a cross-head, F^2 , and through the ends of this cross-head pass rods F^3 , which are operated by eccentrics F^4 upon a main shaft, H , of the machine.

50 We have shown nuts f^2 as applied to the upper ends of the rods F^3 , and springs f^3 , beneath the nuts f^2 , so as to permit the feeder F to be brought to a stop by the bottom of the pocket E , and then to permit the eccentrics to draw down slightly, thus compressing the springs f^3 and exerting a proper amount of pressure upon the filler in the pocket.

55 The rods F^3 pass through eyes in the end of the cross-head F^2 , and therefore the cross-head F^2 swings upon the pivot f' to accommodate itself to the varying positions of the rods F^3 , while to the feeder F is imparted a true rectilineal movement toward and from the apron. The main shaft H has upon it a wheel, h , with which engages a pinion, h' , upon a driving-shaft, h^2 .

60 We will now describe more particularly the construction of the pocket E , reference being had particularly to Figs. 5 to 8, inclusive.

c designates a cross-bar, which extends transverse y between the side frames, and to this cross-bar is secured a plate or projecting flange z , which forms the bottom of the pocket. Projecting upward at one edge of the bed or bottom e is a flange, e' , which is thin and 65 therefore slightly flexible, although of metal, and this flange e' forms a portion of the stationary member of the pocket, while the upper portion of that side of the pocket is formed by a roller, e^2 , which is mounted in stationary 70 bearings. The movable member of the pocket is a stiff bar having a comparatively thin rounded but unyielding edge, and is secured by an arm or arms, e^4 , upon a rock-shaft, e^5 , and to said rock-shaft is fixed an arm, e^6 , carrying a truck-roll, e^7 , on which operates a cam, e^8 , upon the shaft H . Secured to the cross-bar c and extending rearward for some distance, is a bed or table, I , over which the apron D passes, and in which we have represented 75 an opening.

80 Above the apron is a paste-box, J , and a fountain-roll, j , turning therein, and which may be driven by a belt, j' , from a pulley, j^2 , upon the shaft H .

85 j^3 designates the paste-brush, which is supported by curved arms, j^4 , and these arms are fulcrumed upon a rock-shaft, j^5 , which is here represented as below the paste-fountain J . Motion is imparted to the rock-shaft j^5 by an eccentric-rod, j^6 , operated by an eccentric, j^7 , on the shaft H , and which is connected with an arm or disk, j^8 , upon the rock-shaft j^5 . By the eccentric and rod j^7 j^6 the rock-shaft j^5 is swung and the brush j^3 is alternately raised 90 into contact with the fountain-roll j and lowered to the position shown in Fig. 5, so as to deposit the paste upon the wrapper K , and the opening i is formed in the table I , so that as the brush j^3 is pressed downward the wrapper K and the apron D may give way slightly over this opening, and thus enable the brush j^3 to properly apply paste to the wrapper K .

95 The table or bed I is extended rearward of the pocket E sufficiently to permit of the wrapper K being placed accurately in position upon the apron D behind the paste fountain or box J , and as the apron is drawn forward by its connection with the cross-bar A' it of course carries forward the wrapper placed upon it, 100 , and the surplus of length in the apron D between the two adjacent cross-bars A' folds back under the cross-bar, which is behind, as shown at s in Fig. 1, and thus preserves the

portion of apron in front of each cross-bar taut and smooth upon the table or bed I. We have shown arms k, which are secured to the bottom of the paste-box J, and which have a downward resilience, so that as the cross-bars A' pass under said arms a slight downward pressure is exerted upon the cross-bar, and a retarding effect or drag is produced upon the surplus of apron, s, which lies under the cross-bar, as shown in Fig. 1.

It is obvious that if the chains or travelers A and the apron D both move at a uniform speed and continuously the surplus of apron, s, could not be withdrawn from under the cross-bar A' or pulled ahead of the chains A, and it is by the pulling or drawing ahead of this surplus, while a loop of the same portion of apron is contained in the pocket E, that we are enabled to roll the cigarette in the pocket. Upon the piece forming the channel-way F', in which the feeder F works, are rods l, which work in suitable guides, l', and which are connected with the feeder F, so that as said feeder is pressed downward the rods l are likewise pushed downward and engage at the same instant the links of the chains A on opposite sides of the machine, thereby locking the chains in position.

We have before stated that the chain-wheel B² is the one through which the chains are driven, and we will now describe the mechanism, shown particularly in Fig. 4, for accomplishing this purpose. Secured fast upon the shaft B is a gear-wheel, B⁵, and upon this gear-wheel is a pin, b³, which works in an arc-shaped slot, b⁴, in the adjacent chain-wheel B². With the wheel or pinion B⁵ engages a driving-pinion, b⁵, upon the main shaft H, and by the rotation of the main shaft H and the driving-pinion b⁵ in the direction shown by arrow in Fig. 4 the larger gear-wheel, B⁵, is moved in the direction indicated by the arrow in Fig. 4. We have shown a coiled spring, b⁶, for connecting the gear-wheel B⁵, which is fast on its shaft B, with the adjacent chain-wheel B², which is loose on said shaft, and this spring acts to uncoil itself and turn the chain-wheel B² ahead relatively to the gear-wheel B⁵. In other words, so long as the chains A are free to move, the pin b³ in the gear-wheel B⁵ remains at the rear end of the arc-shaped slot b⁴ in the chain-wheel B²; but so soon as the chains A are locked by the pin l descending into them the pin b³ travels ahead in the slot b⁴, and as soon as the chains are again unlocked the chain-wheel B² is moved ahead of the wheel B⁵ by the spring b⁶ and again brings the rear end of the slot b⁴ to the pin b³. Upon the shaft B is an apron-pulling device, which, as represented, consists of a cross-bar or arms, L, having at their ends cross-plates L', extending parallel with the shaft B. This device is fast on the shaft B, and as it is turned it periodically catches the apron D and draws out from under the cross-bar A',

which is behind the pocket, the surplus s, which is retarded thereon.

We will now describe more particularly the operation of the pocket E and the effect of drawing ahead the surplus length of the apron D. The cam e⁸, which is shown in Figs. 5, 7, and 8, comprises three steps. The first step, 1, is of least radius, and when it bears against the truck-roll e¹, as shown in Fig. 8, the movable jaw e³ of the pocket is drawn backward by the spring e⁹, and thus the pocket is opened to its fullest extent. At the instant that the wrapper is brought to a position opposite the pocket and with the principal portion of its length lying behind the pocket, as shown in Fig. 5, the step 2 of the cam e⁸, which is of greater radius, comes against the truck-roll e¹ and presses the movable jaw e³ toward the opposite jaw, this pressure closing the pocket. At the same instant the feeder F has descended and come to about the position represented in Fig. 5, and the movable jaw e³ is held pressing the apron D against the edge of the feeder at the point m, and thereby holds the wrapper K, while the brush j³ descends and applies paste to the wrapper. The wrapper is thus held against any pulling out of place by the brush j³ descending upon it. While the step 2 of the cam e⁸ is passing or traversing the truck-roll e¹ the feeder F completes its downward movement to the position shown in Fig. 6, and thereby forces downward into the pocket E the filler o, cut off by the feeder, the wrapper K, and a loop of the apron D. During this descending movement of the feeder F the locking-pins l have descended into the chains A, and by the downward movement of the feeder F the length of apron necessary to form the loop which is in the pocket E is drawn forward from the surplus of apron behind. The feeder F now commences to rise and finally leaves the pocket E, and at the same instant that it leaves the pocket the third step, 3, of the cam, which is of greatest radius, comes against the truck-roll e¹, and the movable member or jaw e³ is moved to the position shown in Fig. 7, so as to completely close the pocket and close the apron D in, so that its portions will nearly touch each other over the filler and wrapper which are contained in the pocket. As the feeder F recedes upward out of the pocket, the locking-pins l are withdrawn from the chains or travelers A, and by the action of the spring b⁶ the chain-wheel B², and through it the other chain-wheels, B¹ B³, are moved ahead until the rear end of the arc-shaped slot b⁴ comes against the pin b³ in the gear-wheel B⁵. At the instant that the movable jaw e³ of the pocket closes to the position shown in Fig. 7 the apron-pulling device L L' catches the apron and pulls it ahead of the chains, thereby producing a draft on the apron D in the direction indicated by the arrows in Fig. 7 and until the surplus s behind the pocket is drawn forward. This pull upon the apron D pre-

duces the longitudinal travel of the loop thereof which is in the pocket E around the contents of the pocket, and thereby imparts to the contents of the pocket a rolling motion in the direction indicated by the arrows in Fig. 7 and tucks the front edge of the wrapper K, which is turned backward, in under the following portion of the wrapper and rolls the wrapper and filler to form a perfect and clean-made cigarette. We find that this rolling may be very accurately and smoothly done when one member of the pocket, as e^3 , is a roller which is free to rotate, and when the jaw e^3 , constituting the other member of the pocket, is a bar, which, having a comparatively thin edge and being stiff and unyielding, serves in the operation of closing the pocket to bend inward the forward edge of the wrapper, as shown at n in Fig. 7, and so insure the front edge of the wrapper passing in under the portion which is to roll outside it at the commencement of the rolling operation.

A brief reference may be made to the means for operating the feeding-apron G, although such mechanism forms no part of our invention. Upon the shaft H is a cam, p , which acts upon a truck-roll, p' , in a lever, p^2 , fulcrumed at the lower end, p^3 , and a rod, p^4 , connects this lever with a pawl-arm, p^5 , as best shown in Fig. 2. By this common feeding mechanism the feeding-apron G is moved in the direction of the arrows, so that each movement of the rod p^4 and pawl-arm p^5 advances the apron G and the filler upon it to exactly the extent required for a single operation of the feeder and cutter F.

What we claim as our invention, and desire to secure by Letters Patent, is—

1. The combination, with parallel endless chains or travelers and cross-bars extending between them and wheels for moving said chains or travelers, of an apron or webs secured to said cross-bars and having a surplus of length or slack between them, a pocket and a reciprocating blade or feeder on opposite sides of the apron, the feeder serving by its movement to push into the pocket the quantity of filler for a cigarette, the wrapper, and a loop of the apron, and the pocket closing upon its contents as the feeder recedes, and an apron-pulling device whereby the slack in the portion of apron which forms the loop is drawn forward and caused to roll the contents of the pocket to form a cigarette, substantially as herein described.

2. The combination, with endless chains or travelers and cross-bars extending between them and wheels for moving them, of an apron secured to said cross-bars, with slack or surplus length between the bars, a pocket and a reciprocating feeder on opposite sides of the apron, the feeder serving by its movement to push into the pocket the filler and wrapper for a cigarette and a loop of the apron, and

the pocket closing upon its contents as the feeder recedes, a retarder behind the pocket under which the apron passes, and which retards or holds back its surplus length, and an apron-pulling device whereby the slack of the apron is drawn forward from the retarder and through the pocket, thereby rolling the contents of the pocket into a cigarette, substantially as herein described. 70

3. The combination, with the chains or travelers, with their cross-bars, and the apron secured to the cross-bars and having slack between the bars, of the pocket and reciprocating feeder on opposite sides of the apron, the table I behind the pocket to support the apron, and between which and said cross-bars the surplus length of the apron is retarded, and an apron-pulling device whereby the slack of the apron is drawn forward and through the pocket, thereby rolling the contents of the pocket to form a complete cigarette, substantially as herein described. 75

4. The combination, with two endless chains or travelers, cross-bars connecting them, and wheels for driving them, of an apron secured to said cross-bars and having slack in its length between the bars, a pocket and a reciprocating feeder on opposite sides of the apron, the feeder serving by its movement to push the filler and wrapper for a cigarette and a loop of the apron into the pocket, and the pocket closing upon its contents as the feeder leaves it, an apron-pulling device for drawing the slack from the apron and rolling the contents of the pocket into a cigarette, the paste-fountain roller, and the reciprocating paste-brush, whereby paste is taken from said roller and deposited on the wrapper, substantially as herein described. 90

5. The combination, with two endless chains or travelers, cross-bars extending between them, and wheels engaging with them, of the feeder and pocket organized and operating substantially as herein described, locking-pins for locking into the chains or travelers when the feeder enters the pocket, and an apron-pulling device which is free to move independently of said wheels and when the chains are locked to draw forward the slack of apron through the pocket to roll the contents thereof, substantially as herein set forth. 95

6. The combination, with two chains or travelers and cross-bars connecting them, of the shaft B and chain-wheels B^2 B^3 loose thereon, the chain-wheels B^4 and their shaft B' , the gear-wheel B^5 fast on the shaft B and having a pin-and-slot connection, and the spring or yielding connection with the chain-wheel B^2 , the reciprocating feeder and pocket and locking-pins, all organized and operating substantially as herein described, and the apron-pulling device consisting of the arms L on the shaft B, substantially as herein set forth. 100

7. The combination, in a cigarette-machine, of an apron and reciprocating feeder above 105

the apron, a pocket below the apron, consisting of two members, one of which members is composed of a roller, e^2 , in stationary bearings, a stationary bed, e , and a flange, e' , attached to said bed, and the other of which is a stiff unyielding cam-actuated bar, e^3 , having a comparatively thin edge, and an apron-pulling device for drawing through the closed

pocket the apron depressed in the loop therein substantially as herein described.
